(57) **CLAIM**

We claim the ornamental design for a cartridge for coffee machine, as shown and described.

DESCRIPTION

FIG. 1 is a perspective view, from above, of a cartridge for coffee machine embodying our design;

FIG. 2 is a bottom perspective view thereof;

FIG. 3 is a right side view thereof;

FIG. 4 is a left side view thereof;

FIG. 5 is a front view thereof;

FIG. 6 is a rear view thereof;

FIG. 7 is a top view thereof; and,

FIG. 8 is a rear view thereof.
